RUBBER BAND SHOOTER

Joel Robert Heminger, Akron, Ohio

Application October 10, 1938, Serial No. 234,241

4 Claims. (Cl. 124—17)

This invention has, among its objects, the provision of a piece for shooting rubber bands, the construction being such that the movable parts are quickly restored to their normal positions by inherent forces supplied by elastic members, after said movable parts are temporarily drawn out of said normal positions by extraneous forces. A second object is to provide a toy of simple and inexpensive design whose parts are easily accessible and cheap to replace. A third object is to provide a trigger-and-hammer mechanism of novel form and utility, including simple and effective means for stopping, without shock, the forward movement of the upper portion of the hammer when said hammer is caused to swing on its pivot.

It is within the province of the disclosure to improve, generally, and to enhance the utility of rubber band shooters of that type to which the present invention appertains.

With the above and other objects in view, as will appear as the description proceeds, the invention resides in the combination and arrangement of parts and in the details of construction hereinafter described and claimed, it being understood that alterations in the precise embodiment of the invention herein disclosed, may be made, within the scope of what is claimed, without departing from the spirit of the invention.

In the accompanying drawings:

Fig. 1 shows, in side elevation, a hand shooter constructed in accordance with the invention, parts being broken away, and the device being set to shoot a rubber band;

Fig. 2 is a top plan of the band shooter delineated in Fig. 1;

Fig. 3 is a view similar to Fig. 1, the parts being in the positions which they will occupy whilst the rubber band projectile is being shot;

Fig. 4 is a section on the line 4—4 of Fig. 1;

Fig. 5 is a section on the line 5—5 of Fig. 1;

Fig. 6 is a side elevation showing a modified embodiment of the invention, parts being broken away;

Fig. 7 is a top plan of the band shooter shown in Fig. 6;

Fig. 8 is an end elevation of the band shooter depicted in Fig. 6;

Fig. 9 is a fragmental longitudinal section showing, as a modification, a laminated body construction.

In Figs. 1 to 5 of the drawings, there is shown a shooting piece constructed in accordance with the invention. The term "shooting piece" is employed to give notice of the fact that the device

need not necessarily be of the pistol form shown.

The shooting piece comprises a body, denoted generally by the numeral 1, including a stock or grip 2 and a barrel 3. In this particular group of illustrations, there is shown an extension 4 of the body, a little to the rear of the stock or grip 2, this extension being merely incidental to the particular form shown, of the shooting piece. The extension 4 is provided with an upstanding projection 5, which may be considered to be a part of the body.

A slot 6 is formed in the main part of the body 1, immediately to the rear of the barrel 3, and extends downwardly into the grip 2, the slot opening through the forward edge of the grip 2, and through the upper edge of the body 1. The slot 6 has a lower, forwardly prolonged extension 7. The part of the body 1 which defines the upper rear limit of the slot 6, forms a stop 10. In the upper edge of the body, a little forward of the hammer 19, there is shown a notch 11, which may be considered as marking the rear extremity of the barrel 3. This notch 11 is declared to be an important feature of the form 15 of the shooting piece depicted by Figs. 1, 2, 3 and 5 of the drawings, as will be brought out in the explanation hereafter.

The notch 11 is placed in a position with a certain relation to the hammer 19, and is cut to 20 a suitable depth so that the elastic belt 17, which it is designed to retain, shall be held in the circular path of the upper part of the hammer 19. The upper and front part of the slot 6 is prolonged forward a little past notch 11, forming a 25 recess into which hammer 19 can be partially depressed when it is drawn to its extreme forward position. The solid part of the body 1, however, which defines the bottom of this recess, designated by the numeral 18, is designed to be a little 30 lower than the bottom of notch 11, for reasons to become apparent as the description proceeds.

The forward end of the barrel 3 is supplied with a retainer or notch 27, from which the projectile band 26 is stretched back to and around 35 the retainer finger 23 of the hammer 19, as illustrated in Figs. 1 and 2.

The numeral 12 designates a trigger, extended 40 upwardly into the slot 6 and mounted for swinging movement on a pivot member 14, carried by the rear portion of the body 1. The trigger 12 is shaped and mounted with a certain relation to the hammer 19, so that the shoulder or sear 45 15, cut into the upper edge of trigger 12, shall engage a complementary shoulder 21, shaped in the hammer 19, when said hammer 19 is at ap-

proximately its rearmost position. The trigger 12 is provided with a forwardly presented arm 16, adapted to be received in the recess 7, which is another forward extension of slot 6. It is not to be surmised from the drawings that the bounds of slots 6 are to fit so closely to the movable parts as to restrict their movements, with but one exception.

This one exception is the aforementioned stop 10, which determines the rearmost or normal position of the hammer 19, as shown by Fig. 1 of the drawings.

The position of the hammer 19 is well back in relation to the main body 1, so that the projectile band 26 will have full advantage of most of the length of the shooting piece. The hammer 19 is placed partly within the slot 6 but protrudes above the main body 1 and is mounted on a pivot element 20 so that the upper portion of the hammer 19 may be swung forward and backward through an arc, determined by its pivot element 20, and whose extremes are determined by stop 10 at the rear and by the part of elastic belt 17, at the front, which rests in notch 11 and across slot 6.

From the foregoing it will be evident that one of the functions of the elastic member 17 is to serve as a cushion to halt the forward swing of the hammer 19, as will be apparent by reference to Fig. 3 of the drawings. It will also be manifest why the solid portion 18 of the body 1 is below the bottom of notch 11 and, therefore, clear of the part of elastic member 17 which serves as a stopping cushion for the hammer 19.

Figure 5 of the drawings illustrates how the elastic belt 17 passes across the main body 1 and, incidentally, across slot 6 at the position determined by notch 11, from where it passes down and under the aforementioned arm 16 of the trigger 12. By providing an elastic belt 17 of proper tension, which is not critical, it will be seen that trigger 12 will be drawn upward when the hammer 19 is in its rearmost position and held thus until displaced by the finger of the operator.

The hammer 19 is shaped, in its upper portion, to form a forward retaining finger 23 and a rear anchoring lug 22; these two being separated by a notch 24, designed to permit the projectile band 26 to be passed around the retaining finger 23. An elastic member 25 engages the anchoring lug 22 and is slightly stretched to engage the upstanding projection 5 of the body 1 so that it tends to maintain the hammer 19 in its rearmost or normal position.

Referring to Fig. 1 of the drawings, the elastic member 25 has swung the hammer 19 backward against the stop 10, and the elastic member 17 has drawn the forward arm 16 of the trigger 12 upward into the recess 7, so that the shoulder or sear 15 of the trigger 12 has interlocked with the shoulder 21 of the hammer 19. The numeral 26 designates the aforementioned projectile band which is stretched back from the retainer notch 21, at the muzzle, to pass around the retainer finger 23 of the hammer 19, in which condition it may be held so long as the hammer 19 is prevented from swinging on its pivot element 20 by the interlocking of its shoulder 21 with the shoulder or sear 15 of the trigger 12.

It will now be evident that when the operator presses the finger piece of the trigger 12, said trigger will swing on its pivot element 14 so that the shoulder 15 will disengage from the shoulder

21 and permit the hammer 19 to swing on its pivot element 20. Thereupon, the tension of the projectile band 26 will cause the hammer 19 to be drawn forward, despite the slight tension of elastic member 25, and the upper part of the hammer 19 will describe an arc until the angle of the retaining finger 23 has changed to permit the projectile band 26 to slip free and to hurl itself away from the shooting piece in the well known manner of elastic bands. The position of all parts of the mechanism at this stage of operation is depicted by Fig. 3 of the drawings.

When the projectile band 26 has slipped free of the retaining finger 23, the tension of the elastic member 25 will cause the hammer 19 to be quickly drawn back to its rearmost position against stop 10, and when the operator releases the trigger 12, shoulders 15 and 21 will again interlock and a cycle will have been completed, ready for another projectile band to be stretched into place. From the description of this cycle, it will be obvious that the mechanism is self-cocking.

In Figs. 6, 7 and 8, parts hereinbefore described have been designated by numerals already used, with the suffix *a*. The upper portion of the trigger 12a extends out of the upper part of the slot 6a. In the upper or rear end of the trigger 12a there is a notch 28, forming a forward projection or finger 29 and a rear projection or finger 30. It is the projection 30 that comes to rest against the stop 10a, rather than the corresponding part of the hammer 19 in Fig. 1. The band 17a of Fig. 6 corresponds to the band 17 of Fig. 1, in that it is the means whereby the trigger 12a is swung upward until its shoulder 15a engages with the shoulder 21a of the hammer 19a. The resilient band 25a is engaged with the part 22a and, in that respect, the form shown in Fig. 6 is like the form shown in Fig. 1. The band 25a, however, is engaged with the projection 29 of the trigger 12a, rather than with the upstanding body projection of Fig. 1. The band 17a is engaged with the rearward extension 4a of the body 1a and with the projection or finger 30 of the trigger 12a.

The operation of the shooting piece shown in Fig. 6 differs so little from the operation of the shooting piece shown in Fig. 1 that a description of the operation of the form shown in Fig. 6 is believed to be unnecessary.

Figures 4 and 5 indicate that the body 1 is made of one piece of material, for example wood. Figure 9, however, shows that the body may be made of any desired number of layers 31, if a laminated construction is desired. In Fig. 9, parts hereinbefore described have been designated by numerals already used, with the suffix *b*.

Although the elastic band 25a of Fig. 6 is anchored for convenience on the part 29 of the trigger 12a, the band does not serve the trigger in any way. Clearly, the band 25a has no function as a means for returning the trigger 12a to set position.

Having thus described the invention, what is claimed is:

1. A shooting piece for discharging a resilient band projectile, comprising a body and a hammer mounted to swing on the body, the hammer constituting means for retaining a resilient band projectile stretched on the body for discharge and for releasing said projectile when said hammer is allowed to swing on its pivot, a trigger mounted to swing on the body, the trigger constituting means for retaining said hammer in cocked position.

tion and for releasing said hammer to swing on its pivot, and an elastic band passing around the main body and engaging said trigger so as to draw and hold said trigger in cocked position until said trigger is operated to release said hammer, the last specified elastic band being interposed partially in the path of the hammer, to act as a resilient cushion to stop said hammer in its forward movement.

2. A shooting piece for discharging a resilient band projectile, comprising a body and a hammer mounted to swing on the body, the hammer constituting means for retaining a resilient band projectile stretched on the body for discharge and for releasing said projectile when said hammer is allowed to swing on its pivot, a trigger mounted to swing on the body, the trigger constituting means for retaining said hammer in cocked position and for releasing said hammer to swing on its pivot, and an elastic band passing around the main body and engaging said trigger so as to draw and hold said trigger in cocked position until said trigger is operated to release said hammer, the elastic band which engages the trigger and passes around the main body being also interposed partially in the path of the hammer for cushioning said hammer at its extreme forward position, and an elastic band engaging said hammer and other convenient member of

said shooting piece and constituting means for returning said hammer to cocked position, all of said elastic bands being easily accessible for renewal from without the body.

- 5 3. A shooting piece for discharging resilient band projectiles, comprising a body and a hammer mounted to swing on the body, the hammer constituting means for retaining a resilient band projectile stretched on the body for discharge, a trigger mounted to swing on the body and constituting means for retaining the hammer cocked, and an elastic band extended around the body and the trigger, to form a return spring for the trigger, the last-specified band being interposed 10 partially in the path of the hammer, to serve as a hammer cushion when the piece is discharged, the body having a notch in its upper edge, receiving said last-specified band and spacing it from contact with a projectile band which is stretched 15 as aforesaid.
- 20 4. A shooting piece for discharging rubber bands, comprising a band-retaining hammer, a trigger cooperating with the hammer, and a resilient member engaged with the trigger in trigger-returning position and comprising a cushioning portion disposed in the path of the hammer as the hammer moves to band-releasing position.
- 25
